CLAIM

The ornamental design for the electronic effects device, as
shown and described.

DESCRIPTION

FIG. 1 is a Top Perspective View of the electronic effects
device;

FIG. 2 is a Bottom Perspective View thereof;

FIG. 3 is a Top View thereof;

FIG. 4 is a Bottom View thereof;

FIG. 5 is a Left Side View thereof;

FIG. 6 is a Right Side View thereof;

FIG. 7 is a Front View thereof; and,

FIG. 8 is a Rear View thereof.

The broken lines in the drawings illustrate portions of the
electronic effects device that form no part of the claimed
design.
